CLAIM

The ornamental design for a hanging decoration, as shown and described.

DESCRIPTION

FIG. 1 is a front, top perspective view of a hanging decoration, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines immediately adjacent the shaded surfaces depict the bounds of the claimed design whereas all other broken lines in the figures illustrate portions of the hanging decoration that form no part of the claimed design.

1 Claim, 8 Drawing Sheets
